UNITED STATES PATENT OFFICE.

FRED OSCAR STOKKE, OF HAVRE, MONTANA.

AUTOMATIC PISTOL.

1,403,133.

Specification of Letters Patent. Patented Jan 10, 1922.

Application filed April 7, 1919. Serial No. 287,956.

To all whom it may concern:

Be it known that I, FRED O. STOKKE, a citizen of the United States, residing at Havre, in the county of Hill and State of 5 Montana, have invented certain new and useful Improvements in Automatic Pistols, of which the following is a specification.

This invention relates to firearms, and more particularly to firearms in which a 10 coil operated bolt is employed, which are commonly known as automatic pistols.

An object of the invention is to provide an automatic pistol which is comparatively simple in construction, embodying a combined bolt and firing pin which are recoil operated to move them into a cocked or retracted position, and which are operated, through the medium of a spring, upon release by trigger operation for striking and 20 discharging a cartridge in the barrel of the pistol.

Another object of the invention is to provide, in an automatic pistol as specified, a vertically movable locking pin which engages in a notch in the bolt of the pistol for holding this bolt in a retracted position and also to provide a sear operated through the medium of a trigger operated lever, which is in turn 25 operated by the movement of an ordinary trigger to release the bolt and firing pin, for discharging a cartridge, and also to provide means for feeding new cartridges into the breech or barrel of the pistol during the 30 operation thereof.

Another object of this invention is to provide a novel form of safety catch to prevent accidental discharging of the pistol, which comprises a stock carried pawl pivotally mounted and adapted to be moved into the path of an enlargement formed upon the bolt of the pistol for preventing contact of the firing pin with a cartridge upon accidental operation of the trigger or for holding 40 the pistol mechanism in a "safety" position when the pistol is not in use.

Other objects of the invention will appear in the following detailed description, taken in connection with the accompanying drawings, forming a part of this specification and in which drawings:

Figure 1 is a side elevation of the improved automatic pistol.

Figure 2 is a longitudinal section through 55 the improved automatic pistol, showing the

bolt and firing pin in a retracted or cocked position,

Figure 3 is a longitudinal section through the automatic pistol showing the firing pin and bolt in a "safety" position. 60

Figure 4 is a fragmentary horizontal section through the pistol.

Figure 5 is a fragmentary end elevation of the pistol illustrating the safety catch.

Figure 6 is a detail perspective of the 65 trigger lever, and

Figure 7 is a detail perspective view of the sear.

Figure 8 is a fragmentary section through the pistol showing the operation of the ejec- 70 tor.

Referring more particularly to the drawings, 1 indicates the frame of the pistol which has a stock or hand grip 2, thereon and projecting downwardly therefrom and 75 to which is also connected a barrel 3. The barrel 3 may be connected to the frame 1 in any suitable manner and the frame is preferably made up so that the side plate, indicated at 4, may be removed for access to 80 the mechanism of the pistol, the said side plate being detachably connected to the frame proper by means of removable screws 5.

The hand grip 2 is hollow, and receives 85 therein the cartridge magazine 6 from which the cartridges indicated at 7 are fed, to the breech of the barrel 3, as shown in Figures 2 and 3 of the drawings.

The magazine structure 6 is similar to 90 that disclosed in the application filed November 30, 1917, Serial No. 204693, including the follower 8, which is urged upwardly for feeding cartridges in front of the breech block 9 of the pistol by a follower spring 95 10. The magazine 6 is held in the hand grip 2 by a suitable magazine lock 11 comprising a spring controlled pivoted lever 12 having a knurled head 13 which engages over a portion of the outer end of the magazine to retain it in place. 100

The breech block 9 is slidably mounted in the frame 1, and is normally held in engagement with the inner end of the barrel 3 by the recoil spring 14, the forward end of 105 which engages the rear end of the breech block, it being confined in its proper position by a sleeve 15. The rear end of the recoil spring 14 extends into a recess 16 formed in the abutment block 17 and it abuts 110

the inner end of this recess as clearly shown in Figures 2 and 3 of the drawings.

The breech block 9 has a pair of side plates 18 formed thereon, the outer surface of which is broken, as shown in Figures 1 and 4 of the drawings and which slidably engage the sides of the frame 1 for guiding the movement of the breech block.

The breech block 9 is provided with a central opening 19, the forward end of which is partially closed by an upstanding lug 20, leaving a comparatively small opening 21 through which the striker 22 of the firing pin 23 is adapted to extend for striking the rim of a cartridge 7 placed in the breech of the barrel 3 for discharging or exploding the said cartridge. The firing pin 23 is formed upon the forward or inner end of the bolt 24 of the automatic pistol and this bolt 20 extends slidably through a guiding opening 25 formed in the abutment block 17. A spring 25' is coiled about the bolt 24 and its inner end engages the rear end of the firing pin 23, it being engaged in the sleeve 15 while its rear end engages the inner end of the recess 16.

After the pistol has been operated for firing a cartridge in the barrel, the recoil action from the discharge of the cartridge 30 will force the bolt 24 and firing pin 23 rearwardly in which rearward or retracted position it will be retained by the engagement of the lug or extension 27 formed upon the locking pin 28 in the notch 29 which latter notch is formed in the bolt 24. The bolt 24 is shown locked in its retracted position in Figure 2 of the drawings.

The locking pin 28 is normally urged upwardly for forcing the lug 27 thereof into the notch 29 by a coil spring 30 seated in a suitable well or recess 31 in the frame 1 of the pistol. The locking pin 28 is further provided with a notch 32 formed therein, in which the tongue 34 of the sear 35 engages. The sear 35 is pivotally mounted upon a pin 36 carried by the frame 1, and it includes the central substantially cylindrical portion from which the projection 36' which carries the tongue 34, extends tangentially and it 50 also has a shoulder 37 which is normally held in a vertical position and faces the rear end of the pistol, formed thereon. The shoulder 37 is formed upon the opposite side of the pivot of the sear from the projection 36 and it is engaged by the upstanding lug 38 formed upon the trigger lever 39. The trigger lever 39 has a laterally extending pin 40 carried at its end remote from the lug 38 and this pin engages in a suitable 55 recess formed in the trigger 42. The trigger 42 is pivoted, upon a pin 43, and in a suitable recess 44 to allow free movement thereof and it has a finger gripping or engaging portion 45 formed thereon which extends into 60 the space surrounded by the trigger guard

46. The trigger 42 is normally held in a forward position by a spring 47 and when held in such position the lug 38 is maintained in engagement with the shoulder 37. The trigger lever 39 has an upstanding projection 48 formed thereon which extends into the recess 49 in the frame 1, in which the breech block 9 reciprocates. This upstanding lug 48 is normally maintained upwardly in the path of the breech block 9 by 75 a suitable spring 50.

The bolt 24 has a knurled head 51 upon its outer end and also an enlargement 52 thereon, so that at the initial operation of the pistol, the bolt 24 may be retracted manually by gripping this knurled head 51 and upon this retraction of the bolt, the spring 30 will force the locking pin 28 upwardly, to move the lug 27 into the notch 29 and lock the bolt in its retracted position, to be released, by the rearward movement of the lower end of the trigger 42. The rearward movement of the portion of the trigger 42 below its pivot pin 43 will move the upper end of the trigger forwardly, moving the trigger lever 39 forwardly a short distance, and rocking the sear 35 to force the locking pin 28 downwardly, releasing the bolt 24 and allowing it to be projected or forced forwardly by the expanding action of the 95 spring 25'. The firing pin 23 is carried by or formed integrally upon the bolt 24 and will, consequently, be projected forwardly with the bolt and the striker 22 thereon will engage the rim of the cartridge 7 in the 100 breech of the barrel 3 and explode this cartridge.

The recoil action of the exploding cartridge will force the breech block 9 and also the firing pin 23 and bolt 24, rearwardly, depressing the trigger lever 39 by the riding of the breech block over the upstanding lug 48, allowing the sear 35 to rock under action of the spring 30 to permit the lug 27 to be forced into the notch 29 to lock the bolt in 105 its retracted or cocked position.

The breech block 9 has an extractor pawl 52' pivotally carried thereby, the bill end 53' of which is held in engagement with the rim of a cartridge 7 by a spring 54' so that 110 upon the rearward or retracted movement of the breech block by the recoil of the cartridge the shell thereof will be extracted from the barrel 3 and after the innermost end of the cartridge has passed out of the 115 barrel, and into the open space left by the retracted breech block, the action of the ejector 55' will force the spent shell out of the pistol structure and a new cartridge will be fed or moved upwardly in front of the 120 breech block, out of the magazine 6 by the action of the follower spring 10 so that upon the return of the breech block to its normal position under action of the recoil spring 14, the new cartridge will be forced into the 125 130

breech of the barrel 3 for firing upon the next operation of the trigger 42.

The ejector 55', which co-acts with the extractor 52' for ejecting a spent shell, as shown in Figure 8 of the drawings, has the threaded shank 56' formed thereon which is threadably engaged in an opening formed in the barrel 3 and adjacent portion of the stock 1. When the bolt or firing pin 23 is in an operative position for discharging the cartridge 7, the ejector 55' is seated in a suitable recess 57' formed in the breech block 9. The ejector 55' has a lateral shoulder 58' thereon which engages against the rim of a shell and tilts the shell for ejecting it through the opening formed upon the recoil of the breech block 9.

A safety catch structure is provided for preventing the accidental discharge of the cartridge in the pistol and it comprises a catch member 53 which is pivotally mounted, by a suitable pin 54 to the rear end of the frame 1. This pivoted catch has one end 55 shaped to fit partially about the bolt 24 and a laterally extending projection 56 is formed upon the opposite end which is hollow, forming a seat for a spring 57 which engages a ball 58 and forces it outwardly into recesses 59 and 60 formed in the rear end of the frame 1. When the cap 53 is positioned so that the ball 58 will be seated in the recess 59 the end 55 of the latch will engage the bolt 29 and upon forward movement of the bolt, this end 55 will engage the end enlargement 52 preventing contact of the striker 22 with the cartridge 7, and consequently preventing explosion of the cartridge. When the lever or cap 53 is rocked upon its pivot so that the ball 58 will be engaged in the recess 60, the end 55 will be moved out of the path of the enlargement 52, and the bolt 24 and firing pin 23 will be allowed to move forward to the limit of their movement for firing the cartridge in the barrel.

The barrel 3 has a front sight which may comprise a rigid portion 61 and a pivoted portion 62 if desired, while a rear sight 63 is adjustably connected to the abutment block 17. The rear sight 63 has a threaded shank 64 formed thereon which is threaded in a suitable recess in the abutment block 17 which recess preferably communicates with the recess which receives the locking pin 28 and a spring 30 to facilitate the mounting of these elements in the pistol mechanism.

Changes in details may be made without departing from the spirit of this invention, but

60 I claim:

1. In an automatic pistol, the combination with a frame having a longitudinally extending bore therein, of a bolt slidably mounted in the bore, said frame having a vertically extending opening bisecting the

horizontal bore, a rear sight fitted in the upper end of said vertical opening, a pin slidably mounted in the vertical opening and arranged below the bolt, the bolt having a notch formed therein arranged to be engaged by the pin when the bolt is in its firing position, an expansion spring arranged in the vertical opening and arranged to engage said pin to normally hold the same in engagement with the bolt, a pivoted sear arranged in the frame and operatively connected to the bolt, a trigger, and a trigger bar pivotally connected to the trigger and arranged to engage said sear.

2. In an automatic pistol, the combination with a frame, of a breech block slidably carried by the frame, the block having a seat formed in the lower surface thereof, a bolt slidably mounted in the breech block and in the frame, a firing pin carried by the bolt, the bolt having a notch formed therein, a right angularly positioned spring pressed vertically disposed pin slidably mounted in the frame and located below the bolt and arranged to engage in the notch formed in the bolt, a pivoted sear disposed in front of the pin, a rearwardly extending finger formed on the sear arranged to engage the pin, the lower end of the sear having a shoulder formed thereon, a trigger, a trigger bar pivotally connected to the trigger and having a nose formed on the rear end thereof adapted to engage the shoulder of the sear, a projection formed on the trigger bar adapted to fit in said seat whereby the nose formed thereon can engage the shoulder on the sear, and spring means urging the trigger bar projection into the seat and in engagement with the breech block.

3. In an automatic pistol, the combination with a frame, of a bolt slidable in the frame arranged to project rearwardly therefrom, a firing pin carried by the bolt, spring means normally urging the firing pin into firing contact with a cartridge, means arranged to engage the bolt to hold the same in firing position against the tension of the spring, means to move said bolt engaging means out of engagement with the bolt, a vertically disposed safety latch pivotally carried by the rear end of the frame and arranged exteriorly of the frame, an extension formed on the latch arranged to partially encircle the bolt, a head formed on the rear end of the bolt and disposed outwardly of the frame and arranged to engage said extension of the latch when the extension of the latch is thrown in engagement with the bolt, and a spring locking member carried by the latch arranged to engage the frame to hold the extension into and out of operative position with the bolt.
